LAST REMOVING MACHINE

Sidney Hawkes, Rushden, England, assignor to Fred Hawkes (N.V. Engineers) Limited, Rushden, England, a British company

Filed Mar. 7, 1963, Ser. No. 263,643

Claims priority, application Great Britain, Mar. 31, 1962,

12,487/62

9 Claims. (Cl. 12—15.1)

This application is a continuation-in-part of my prior application Serial No. 158,181, filed December 11, 1961, and now Patent No. 3,091,787.

This invention is concerned with last removing machines such as are used in the boot and shoe industry for separating a fabricated or partially-fabricated shoe (or similar item of footwear) from a last on which it has been made. All such articles will, for convenience, hereinafter in this specification be assumed comprehended in the term "shoe."

Machines of this character are provided with an upstanding jack pin on which the last, carrying the fabricated shoe, is mounted with the pin entering the hole provided in the crown faces of lasts for support in this way during the actual manufacture of the shoe thereon. The machines for this purpose also include a thrust device (which can take various forms) which is then arranged to be operated to engage the counter of the shoe and to lift it so that the shoe (which is, of course, sole upwards in this condition) will be pushed or slipped off the last.

An object of the present invention is a machine of the kind stated which caters for an improved shoe-slipping operation.

A further object is a machine in which pieces of foot-wear of different sizes, and sometimes of different heel contour, can be more efficiently, more quickly and often less harshly dealt with by controlling the action of the stripping device.

The machine which forms the subject of the present invention comprises a last support, a stripper device, means to bring about a primary relative movement between the last support and stripper device so that the latter will be applied under pressure against a shoe mounted on the last support, a device which yields under the direct mechanical thrust of this pressure to initiate a secondary relative movement between the last support and stripper device whereby the shoe is slipped from the last, and means providing a manually-adjustable and variable setting of the length of said secondary relative movement.

Thus where, as is most usual, the slipping is performed by applying a forward stroke to the stripper device, the arrangement of the present invention can be devised so that the length of this stroke can be quickly varied, with infinite graduation, to the figure judged from experience to be optimum in dislodging the shoe from the last in regard to such factors as care of the shoe and rapidity of operation.

The length of the shoe-slipping stroke can be controlled in various ways, and a very simple method is attained by allowing for screw-threaded adjustment of a stop on the frame or other fixed part of the machine and/or a similar adjustment of an abutment on the moving part of the stripper device which cooperates with this stop. This moving part may, for instance, be a ram carrying the stripper assembly and movable by hydraulic, pneumatic or mechanical impulsion.

In one form, the stop will conveniently be screw threaded on a fixed sleeve around the ram and cooperate with an abutment collar on this ram. The stop may be in the form of a nut which has internal threading mating with external threading on the sleeve, this nut also having a head in the form of a disc or wheel which is accessible

2

from the exterior of the casing, e.g. through an opening in the latter, so that it can be turned by the hand of an operator to adjust its position longitudinally of the ram.

A form of last removing machine equipped in accordance with this invention is illustrated in the accompanying drawings, in which:

FIGURE 1 is a perspective illustration of the complete machine,

FIGURE 2 is a side view of the same with a vertical section through the main frame housing,

FIGURE 3 is an enlarged side elevation of the head assembly of the machine, with parts in vertical section, and

FIGURE 4 is a diagrammatic illustration of the stripper head assembly in association with the pneumatic operating means of the machine.

The machine illustrated comprises a hollow main frame 1 which serves to house the operating parts of the machine and is shouldered at its upper part into a rear shelf-forming portion 2 having a boss 3 through which passes a plunger ram 4 carrying the stripper head assembly of the machine. The machine, in use, will be served by an attendant standing at the front side seen in the perspective view in FIGURE 1.

This head assembly comprises a block 5 which is clamped on ram 4 by screws 6 and has a pair of lateral wings 7 on which are pivoted corresponding lugs 8 on a stripper pad supporting plate 9. As will be observed from the drawings, this plate is arranged at an inclination to the vertical ram 4, and this inclination can be varied, to suit particular requirements, by a set screw 10 threaded in the upper part of the plate 9 and bearing against block 5, and a lower adjusting screw 11 which is threaded into a forward extension piece of the block 5 and has its head bearing against the lower margin of plate 9.

The latter has lateral ears 12 serving to carry the pivot 13 of a stripper pad holder 14 which overlies the front face of support plate 9 and is normally spaced therefrom by compression springs 15. The outermost position of holder 14 is determined by a pin 52 on the holder, which engages in a slot in a link 53 on plate 9. Inserted into this holder 14, and clamped thereto by side cheeks 51, is a rubber stripper pad 16 having a rounded front surface.

It is to be noted also that the holder 14 carries a screwed stud 17 of adjustable length at one lower side, and this cooperates with the head 18 of a switch-operating plunger in a microswitch casing 19. The arrangement is that a predetermined swing of the holder 14 will operate the microswitch, which has been diagrammatically indicated at 20 in FIGURE 4.

Mounted between the side walls of the main frame 1 below a slot 21, extending across the width of the latter at its front shouldered part, is a shaft 22 which has rotatable thereon a casting 23 which includes an upstanding column 24 with a post 25 at its upper end supporting a jack pin 26.

The casting 23 at its lower side and at one end is formed with a depending tapered arm 27 with a pin 28 projecting from its lower end and carrying a roller. This roller is received in a cam slot 29 in the enlarged end of a further arm 30 which is pivoted at its other end, to a pivot pin 31 in a wall of the main frame 1. Pivoted at its lower end on a cross spindle 32 in the frame 1 is an air cylinder 34, the piston rod 35 of which is pivotally coupled by a yoke 36 to arm 30.

Another air cylinder 37 is mounted on a step bearing 38 on the aforesaid base of the main frame 1, and the shoe removing ram 4 is coupled to the piston of this cylinder 37.

A treadle 39, for initiating the various movements

which occur when a shoe is to be removed, is cast in one piece with an arm 33 which is pivotally supported by a pair of spaced lugs 48 on spindle 32. At its rear end, arm 33 cooperates with the plunger 49 of a valve 40 controlling the air supply to cylinder 34 (see below).

The controls for the machine are diagrammatically illustrated in FIGURE 4, and it is to be noted that when the treadle 39 is depressed, the resultant movement of plunger 49 shifts over the valve member in valve 40 and so allows air to pass from a main air line 41 to the lower end of cylinder 34 and the piston rod 35 to be raised. Included in this line is an adjustable restrictor valve indicated at 50.

The line 41 has a branch 42 incorporating a slide valve 43 which is normally closed and is operable by a solenoid in a casing 44. The solenoid windings are connected to the supply mains at 51 via the microswitch 20 of the head assembly, and the arrangement is that when the solenoid 44 is energised by closure of switch 20, it retracts the valve member in 43 and so opens the branch 42 to the underside of the piston in the air cylinder 37 to produce an upward stroke of ram 4.

A normal operation of the machine therefor proceeds as follows.

The operator in front of the machine places a last 45, carrying a shoe 46 to be slipped, sole-uppermost on the jack pin 26. On depression of the treadle 39, the piston 35 of air cylinder 34 is operated and the arm 30 swings upwards to a small extent. The pin roller 28, bearing on the cam edge of slot 29, is consequently moved forwards a small amount and the post 24 accordingly rocked through a small angle to produce a primary relative movement between the post 24 and the pad, i.e. bring the counter 47 of the shoe 46 against the pad 16, i.e. into the position indicated in dotted lines in FIGURE 2, and then with a continuing pressure on this pad until the resistance of compression springs 15 is overcome and the microswitch 20 is closed. By virtue of the substantial length of arm 30 and the large curvature and vertical disposition of the cam edge 29, the movement of the counter 47 is small but continuous, and it is possible to make the pressure-response of the microswitch very sensitive.

It will be noted that the part of the counter 47 against which the pad 16 engages at this time can be adjusted by appropriate setting of screws 10 and 11, if so desired, and that in any event the degree of pressure between the shoe and the pad 16, required to operate switch 20, can be varied by choice of appropriate loading of springs 15 and/or by an adjustment of the length of the stud 17, so as to provide for optimum conditions for shoe engagement and subsequent removal.

This removal is, in fact, performed in response to closure of switch 20, inasmuch that, as explained above, an electric current passes through the microswitch to operate the solenoid actuated valve 43 so as to send an air impulse to cylinder 37 and cause an upthrust of ram 4 and a lifting of the complete head assembly, including the pad 16. The post 24 and last 45 remain stationary (since air continues to be applied to cylinder 34), so that the shoe 46 is slipped smoothly off the last with a rolling action.

Now as has been made clear in the foregoing, it is an object of the present invention to be able to provide for a variable control of the length of stroke of the pad 16, and to this end in the example illustrated the boss 3 at the upper part of the casing 1 is formed with sleeve 53 surrounding the ram 4, and depending into the casing. The lower end of this sleeve is externally threaded to receive a corresponding nut 54 having a disc 55 at its upper end forming a hand wheel. As will be observed this disc projects out through an aperture or window 56 in the wall of the casing, so as to be accessible from the exterior, and can be marked to cooperate with a fixed marking on the exterior of the casing so as to identify the dif-

ferent settings of the length of ram stroke produced by rotation of disc 55.

The ram 4 also has an abutment collar 57 pinned thereto for cooperation with the lower edge of the stop nut 54 to determine the upper limit of the ram stroke adjustable by this nut.

It will also be noted that the collar 57 has an apertured arm 58 which is slidable along a guide rod 59 depending from the shelf 2, and that it is also provided with a screw 60 forming an anchorage for one end of a tension spring 61 which is adapted to return the ram 3 to its starting position on collapse of the pneumatic cylinder 37 on release of treadle 39 by the operator.

In the arrangement described above it is assumed that the operating unit is a single acting cylinder with a spring return, but a double-acting cylinder could instead be used. In instances where a return spring is used this could be a compression spring in the cylinder or fitted to the ram externally of the cylinder, instead of the external tension spring actually illustrated.

I claim:

1. A fast removing machine comprising a last support, a stripper device, means to bring about a primary relative movement between the last support and stripper device so that the latter will be applied under pressure against a shoe mounted on the last support, means for yielding under the direct mechanical thrust of this pressure to initiate a secondary relative movement between the last support and stripper device whereby the shoe is slipped from the last, and means providing for a manually-adjustable variable setting of the length of said secondary relative movement.

2. A last removing machine comprising a last support, a stripper device normally parted from said last support and a lasted shoe thereon, pneumatically-operated means for producing relative closing movement between the last support and stripper device, means responsive to a predetermined contact pressure between the stripper device and a lasted shoe on the last support to provoke a movement of this stripper device transverse to the direction of said closing movement to slip the shoe from the last, stop means along the path of transverse movement of said stripper device, and means accessible from the exterior of the machine for adjusting the position of said stop means.

3. A last removing machine comprising a frame, a last support movably mounted on said frame, a stripper device movably mounted on said frame, means operable to move said last support towards said stripper device, thereby to apply a lasted shoe on said last support against said stripper device, means responsive to predetermined contact pressure between the lasted shoe and stripper device to move said stripper device relatively to said frame and said last support, and variable means for adjusting the last-mentioned movement of said stripper device.

4. A last removing machine comprising a frame, a last support on said frame, a stripper device on said frame and normally parted from said last support, closing means for producing relative movement in a closing direction between the last support and the stripper device, stripper operating means for producing a shoe-slipping movement of said stripper device in a direction transverse to said closing direction, an adjustable stop on said frame terminating the shoe-slipping movement of said stripper device, and means responsive to predetermined pressure application between said last support and stripper device to operate said stripper operating means.

5. A last removing machine comprising a frame, a last support on said frame, a stripper device on said frame and normally parted from said last support, said stripper device including a part which is yieldable relatively to the remainder, closing means for producing relative movement in a closing direction between the last support and the stripper device, stripper operating means for producing a shoe-slipping movement of said stripper device in a direction transverse to said closing direction, manually-

adjustable variable means to determine said shoe-slipping movement of said stripper device, and means responsive to a predetermined yielding of said yieldable part of the stripper device to trigger said stripper operating means.

6. A last removing machine comprising a frame, a last support pivotable on said frame, a stripper device on said frame and normally parted from said last support, fluid-operated means, including a cam transmission, for producing relative movement in a closing direction between the last support and the stripper device, stripper operating means for producing a shoe-slipping movement of said stripper device in a direction transverse to said closing direction, means responsive to predetermined contact pressure between said stripper device and a shoe on said last support to operate said stripper operating means, and manually-settable stop means to adjust the length of stroke of said stripper device in said transverse direction.

7. A last removing machine comprising a frame, a last support pivotable on said frame, a stripper device on said frame and normally parted from said last support, and a pneumatic operating system which comprises a first air cylinder to pivot the last support and cause a lasted shoe on said support to be closed against the stripper device, a second air cylinder to move the stripper device to slip the shoe from the last, adjustable stop means to control the length of shoe-slipping movement of said stripper device, a mechanically-operable valve controlling the air

supply to said first cylinder, and a solenoid valve operable in response to a predetermined pressure between the shoe and stripper device to open the air supply to said second air cylinder.

5 8. A last removing machine as claimed in claim 4, further including a fixed sleeve on said frame, screw threaded means mounting the stop on said fixed sleeve, a reciprocable member passing through said sleeve, and means mounting the stripper device on said reciprocable member, said member having an abutment member cooperating with said stop.

10 9. A last removing machine as claimed in claim 8 in which the stop is a nut threaded on said sleeve, said machine further including means mounting a large-diameter wheel on said nut and projecting through an opening in said frame.
